UNITED STATES PATENT OFFICE.

GEORGE ROMNEY STEWART, OF LOS ANGELES, CALIFORNIA.

COMBINED CIGARETTE HOLDER AND LIGHTER.

Application filed November 6, 1928. Serial No. 317,537.

This invention relates to new and useful improvements in cigarette holders and lighters and aims to provide a combined device for use in automobiles and other vehicles, homes, offices, and the like whereby cigarettes may be singly delivered and lighted immediately subsequent to the delivery thereof for obviously saving time and overcoming the necessity of using matches, separate lighters or other 10 igniting devices separate from the present combined holder and lighter.

Generally speaking the present invention consists of a chamber for the cigarette constructed to receive a plurality of cigarettes 15 arranged in longitudinal superposed condition and having means at the lower end of the chamber whereby to singly withdraw the same therefrom, means being located adjacent thereto for bringing about the lighting of the 20 cigarette at one end thereof.

An important object of the invention is to provide a device of this character that is of extremely simple construction and inexpensive of manufacture, and one that is highly 25 efficient in its operation and well adapted for all the purposes intended.

With the foregoing and other objects in view as the nature of the invention will be better understood the same comprises the 30 novel form, combination and arrangement of parts hereinafter more fully described, shown in the accompanying drawings and claimed.

In the drawings wherein like reference characters indicate corresponding parts 35 throughout the several views:

Figure 1 is a front elevation of the combined device.

Figure 2 is a detail longitudinal transverse section taken substantially upon the line 2—2 40 of Figure 1.

Figure 3 is an enlarged horizontal section through the lower end of the device taken substantially upon the line 3—3 of Figure 2, and

Figure 4 is a fragmentary section through the cigarette receiver taken substantially upon the line 4—4 of Figure 3.

Now having particular reference to the drawing my novel combined device consists 50 of a cigarette chamber or housing 5 of predetermined length and of an area in horizontal and transverse cross section to loosely receive a plurality of superposed and horizontally arranged cigarettes A. Arranged 55 within an opening in the front wall of this chamber is a glass panel 6 in order that the

cigarettes within the chamber may be readily viewed. The upper end of this chamber is open and provided with a suitable lid 7, while depending from the center of the lid at the 60 inner side thereof is a chain or other flexible element 8 to the lower end of which is secured a weighted follower 9 resting upon the uppermost cigarette and serving to normally force the cigarette in a downward direction. 65

The lower end of this chamber 5 is open, while the front wall at this lower open end terminates in slight spaced relation with the lower end of the back wall as clearly disclosed in Figure 2. The lower end of this 70 chamber 5 is constructed with or arranged within a box-like housing 10 open at its top side forwardly of the chamber 5 and also open at its forward end as also illustrated in Figure 2. The lower open end of the chamber 5 75 terminates in spaced relation with the bottom wall of this housing so that the cigarettes A may drop singly into the housing, and be moved forwardly without engaging the forward wall of the chamber. 80

The bottom wall of the housing 10 directly beneath the lower end of the chamber 5 is provided with a guide member 11 freely slidable through which is a stem 12 the forward end of which is bent to provide a finger engaging hook 13 whereby said stem may be moved forwardly. The rear end of this stem is provided with an upwardly and then forwardly extending finger 14, the inner end of which normally terminates directly in back of the 90 rear wall of the chamber 5 and is provided at this end with a horizontal curved plate 15 for engaging the lowermost cigarette a in the chamber 5 so as to move the same forwardly into the cigarette receiving chamber designated generally by the reference character 95 16. Between this finger 14 and the rear wall of the housing 10 is a retractile coil spring 17 for the purpose of normally returning this finger 14 and stem 12 to the position illustrated in Figure 2. It is obvious that the bottom wall of the housing 10 in back of the chamber 5 be provided with a slot through which the connecting portion between the 100 stem 12 and finger 14 extends. 105

The cigarette receiving chamber 16 is formed within the housing 10 as an integral part of the housing, and the lower end of the chamber 5 if desired. However, this construction may be provided in any suitable manner. 110 At the forward end of one of the side walls of the receiver 16 forwardly of the chamber 5

there is located a lighting unit 18 equipped with a coil 19 that projects through an opening in the wall of the receiver, and into said receiver as clearly illustrated in Figure 3 so that the adjacent end of a cigarette being projected into the receiving chamber will contact with said coil.

This coil has electrical connection with a storage battery or other source of electrical current through the medium of a pair of normally separated spring contacts 20-20 located upon the adjacent end wall of the housing 5 and inside of said housing and in back of the unit 18. Connected to the rear end of the cigarette ejecting finger 14 is a cross bar 21, the end thereof adjacent the contact 20-20 being provided with a forwardly extending contact engaging finger 22, so that when the stem 12 is pulled forwardly, this finger 22 will engage the rearmost spring contact for forcing it into engagement with the other contact which will result in the closing of the circuit to the coil 19 of the lighter unit 18.

In opposed relation with this coil 19, the opposite end wall of the receiving chamber 16 is provided with a plurality of perforations 23, while attached to the outer side of this wall around said perforation is the nipple 24 of a collapsible air bulb 25. This bulb 25 is contacted by the forward plated end 26 of a forwardly extending finger 27 provided upon the adjacent end of said cross bar 21. Obviously as the cross bar 21 is moved forwardly the bulb 25 will be collapsed so that when the bar is released the bulb on expanding will suck air through the opposite end of the cigarette in engagement with the coil causing the lighting of the cigarette.

The forward end of the bottom wall of the cigarette receiving chamber 16 is provided with an upturned skirt portion 28 to prevent the accidental rolling of the cigarette from the receiver. Furthermore, the bottom wall

of the receiving chamber directly in back of this skirt 8 is provided with an upwardly extending rolled portion 29 to prevent the accidental return movement of the cigarette within the receiving chamber.

In view of the foregoing description when considered in conjunction with the accompanying drawings it will be apparent that I have provided a novel, simple and useful combined cigarette holder and lighter that is well adapted for all the purposes heretofore designated, and even though I have herein shown and described the invention as consisting of certain detail structural elements it is nevertheless to be understood that some changes may be made therein without affecting the spirit and scope of the appended claim.

Having thus described the invention, what I claim as new and desire to secure by Letters Patent is:

In a cigarette dispenser; a magazine; a cigarette receiving bracket mounted adjacent said magazine; an electrical igniter and a collapsible bulb mounted at opposite ends of said bracket; an ejector associated with said dispenser; a switch controlling said igniter; and mechanism for actuating said ejector, bulb, and switch in a predetermined order; the said mechanism comprising a slideable bar mounted in the dispenser transversely of and to the rear of said magazine; the said bar having formed thereon a plurality of integral forwardly projecting arms of unequal length, the said bar and arms being positioned with respect to said ejector, bulb and switch respectively, to eject a cigarette, compress said bulb, and actuate said switch on the forward stroke thereof, and to allow said bulb to expand to produce a suction, and cut off said switch on the return stroke.

In testimony whereof I affix my signature.

GEORGE ROMNEY STEWART.
